UNITED STATES PATENT OFFICE.

WILLIAM B. FENN, OF NEW YORK, N. Y., ASSIGNOR TO MARGARET FENN, OF PORT WASHINGTON, NEW YORK.

PROCESS OF STERILIZING CANNED FRUITS, VEGETABLES, OR THE LIKE.

1,365,673.

Specification of Letters Patent. Patented Jan. 18, 1921.

Application filed May 5, 1917. Serial No. 166,605.

To all whom it may concern:

Be it known that I, WILLIAM B. FENN, a citizen of the United States, residing at New York, in the county and State of New York, have made a certain new and useful Invention in Processes of Sterilizing Canned Fruits, Vegetables, or the like, of which the following is a specification.

This invention relates to a new and improved process for sterilizing canned fruits, vegetables, and the like.

The object of the invention is to provide an efficient process for quickly, easily, efficiently and cheaply sterilizing canned goods and particularly vegetables, fruits, or the like.

Further objects of the invention will appear more fully hereinafter.

The invention consists substantially in the construction, combination, location, relative arrangement of parts and the new and improved process of utilizing the same, all as will be more fully hereinafter set forth, as shown by the accompanying drawing and 25 finally pointed out in the appended claims.

Referring to the drawing:

Figure 1 is a view in section of a sterilizing apparatus employed in connection with my invention.

30 Fig. 2 is a segmentary view in section showing the principle involved in sealing the can as contemplated in my invention.

Fig. 3 is a similar view showing the can temporarily sealed prior to being permanently seamed, as is well understood in the art.

The same part is designated by the same reference numeral wherever it occurs throughout the several views.

40 It is among the special purposes of my present invention to provide means for sterilizing the can and its contents with its cap or cover in place and to seal the can with pressure and heat within the can during the sterilization process. I have found that by this process the contents of the can are completely sterilized. A disadvantage of the process now in use is that the can is subjected to approximately 15 pounds pressure and a temperature of 250° F. to which it is subjected from approximately 30 minutes to an hour and 15 minutes according to the products treated. This length of time is generally necessary to have the heat reach 55 the center of the contents of the can. It is

obvious that such a length of time in connection with the heat is apt to cook the surface contents of the can and to render the contents unequal with respect to the degree of temperature to which they have been subjected.

It is also among the special purposes of my present invention to provide a process which heats all of the contents of the can to the same temperature in approximately the same time, which time is materially shortened.

My invention also makes it possible to eliminate to a great extent the handling required in sterilizing cans as is now the case where cans are sealed and then placed, in large quantities, in a chamber to be acted upon by the heat and pressure, to effect the sterilization.

Referring to the drawing, I show at 1 a can of the usual, ordinary construction with a loose top 2 and bottom 3^a which bottom is seamed thereto in the manner well known in the art when supplied to the canner. In accordance with my invention the can 1 is passed through its first seaming stage wherein the bottom 3^a is permanently seamed in place and the top 2 is temporarily and loosely clenched in place, as shown best in Fig. 2, allowing a little space or aperture between the can and the cover for a purpose to be hereinafter described. The can 1 is then placed with loose cover 2 on a movable platform 3 adapted to be forced or moved into chamber 4 to close said chamber. A handle 5 forming part of or secured to the platform 3 and operated in any suitable manner, is sufficient for this purpose. The chamber 4 is formed by the walls 4 and 5^a between which walls is a space 6 which I will hereinafter refer to as the steam chamber. A pipe 7 controlled by valve 8 admits steam into the chamber 6 and a pipe 9 controlled by valve 10 allows the exhaust of the steam from the chamber 6. The wall 5^a is provided throughout its surface with ports 11 all positioned to direct a flow of steam from the chamber 6 directly to the can 1. Any number of these ports 11 may be employed, my invention not being limited to the number, but in accordance with my invention I desire to have the steam directed therethrough directly to the can. What takes place within the chamber 4 is as follows:—The chamber being completely 110

closed by the support 3, the exhaust valve 10 being closed, the valve 8 is opened, preferably comparatively slowly, say from five to ten seconds being required to completely open this valve. Steam is admitted through the pipe 7 into the steam chamber 6 of the dome shaped chamber 4 preferably at a suitable pressure of from 2 to 50 pounds, according to the product treated. The steam in the chamber 6 then passes through the numerous ports 11 in the wall 5^a directly impinging upon the can and subjecting the can to the temperature incident to the steam pressure, which is approximately from 150° F to 300° F. The steam within the chamber 4 percolates through the comparatively loose connection between the can 1 and its cover 2 and boils up through the liquor or the contents of the can, thereby raising the temperature of the entire contents of the can to substantially the same degree and at substantially the same time as the exterior surface of the can. Due to this fact the length of time to which the can is subjected to the pressure is materially shortened to from 2 to 10 seconds. I then temporarily seal the cover in its place on the can to prevent the steam or pressure from escaping therefrom. I accomplish this by what I will term a punch 13, which comprises a spider frame secured to a rod 14 which passes through the top of the chamber 4, through a suitable bushing 15 and which is adapted to fit over the can 1, so that its bottom or foot 16 flattens the overlapping portions of the cover 2 and the can 1 to thereby seal the pressure therein. This prevents the contents of the can, and the steam and pressure therein, from escaping when the support 3 is removed and the can is righted and the same is put through the seamer to permanently seal the cover and can in the usual manner, well known in the art.

The punch 13 is made cut away wherever possible to give a web effect, to thereby offer as little obstruction as possible to the flow of the steam from the steam chamber 6 through the ports 11 of the wall 5^a. If desired, and as shown, the top of the can 2 may be slightly waved, or crimped, as indicated, to insure proper space between the elements to thereby allow the steam to enter the can when in the chamber 4. For the purpose of rendering my invention more apparent to those skilled in the art, I will briefly describe the operation and the entire process including the various steps therein toward which my invention is directed. The material to be canned is placed in the can 1 in the usual way, and the can is sent through the first seamer which temporarily seams the top of the can 2. The can is then inverted and placed upon the support 3 and the support 3 is moved in place. The valve 8 is then opened and the can is subjected to

the steam the required length of time, which steam is of the required pressure. The punch 13 is then pushed downwardly by means of the rod 14 secured thereto and the top 2 of the can is temporarily seamed to the can 1. The valve 8 is then closed and the exhaust valve opened. When the steam has escaped from the chamber 4 through the exhaust valve 10 and pipe 9, support 3 is removed and the can taken therefrom and passed through the second seamer, which permanently seams the top or cover 2 to the can.

Having now set forth the objects and nature of my invention and a process embodying the principles thereof, what I claim as new and useful and of my own invention and desire to secure by Letters Patent is:

1. The process of sterilizing canned goods which consists in subjecting the can and its contents to the action of heat and pressure before sealing the can, and then sealing the can while the same and its contents are in a heated condition and still subjected to the pressure on the exterior and interior thereof. 90

2. The process of sterilizing canned goods which consists in subjecting the can and its contents to the action of steam under pressure before sealing the can and then sealing the steam under pressure within the can. 95

3. The process of sterilizing canned goods which consists in subjecting the can and its contents to the action of steam under pressure, in a closed receptacle, before sealing the can and finally sealing the steam under pressure within the can while the same is in said receptacle. 100

4. The process of sterilizing canned goods which consists in placing the can with its cover partially sealed in a closed receptacle, 105 admitting steam into said receptacle to completely surround the can and to enter the same, and then completely sealing the cover of the can.

5. The process of sterilizing canned goods 110 which consists in placing the can with its cover partially sealed in a closed receptacle, admitting steam into said receptacle to completely surround the can and to enter the same, then completely sealing the cover of 115 the can, and finally exhausting the steam from said receptacle.

6. The process of sterilizing canned goods which consists in placing the can with its cover partially sealed in a closed receptacle, 120 admitting steam into the receptacle in fine jets to allow the steam to surround the can and enter the same, and sealing the cover on the can to retain the steam therein.

7. The process of canning foods which 125 consists in placing the filled can with its cover loosely attached in an inverted position within a steam chamber, admitting steam to the chamber whereby the steam forces its way past the cover into the can 130

agitating and sterilizing the food, and then crimping the cover on the can while within the chamber whereby the steam is confined in the can, and finally removing the can and 5 permanently sealing it.

8. The process of canning foods which consists in placing the filled can with its cover loosely attached in an inverted position within a steam chamber, admitting 10 steam to the chamber whereby the steam forces its way past the cover into the can agitating and sterilizing the food, and then crimping the cover on the can while within the chamber whereby the steam is confined 15 in the can, then exhausting the steam from said chamber, and finally removing the can and permanently sealing it.
9. The process of canning foods, which consists in placing the filled can with its 20 cover loosely sealed, within the steam chamber, admitting steam to the chamber, where-

by the steam forces its way past the cover into the can agitating and sterilizing the food and then completely sealing the cover on the can while within the chamber, where- 25 by the steam is confined in the can, and finally removing the can.

10. The process of canning foods, which consists in placing the filled can with its cover loosely sealed, within the steam cham- 30 ber, admitting steam to the chamber, whereby the steam forces its way past the cover into the can agitating and sterilizing the food and then completely sealing the cover on the can while within the chamber, where- 35 by the steam is confined in the can, then exhausting the steam from said chamber, and finally removing the can.

In testimony whereof I have hereunto set my hand this 28th day of April A. D., 1917. 40

WILLIAM B. FENN.
